UNITED STATES PATENT OFFICE

143,396

DESIGN FOR A MICROSCOPE

Oscar C. Blomgren, Evanston, Ill.

Application August 30, 1945, Serial No. 121,745

Term of patent 14 years

(Cl. D57—1)

To all whom it may concern:

Be it known that I, Oscar C. Blomgren, a citizen of the United States, residing at Evanston, in the county of Cook and State of Illinois, have invented a new, original, and ornamental Design for a Microscope, of which the following is a specification, reference being had to the accompanying drawing, forming part thereof.

In the drawing:

Figure 1 is a side elevational view of a microscope showing my new design;

Figure 2 is a front elevational view of the microscope; and

Figure 3 is a top plan view of the microscope of Figure 1.

I claim:

The ornamental design for a microscope, as shown.

OSCAR C. BLOMAGREN.
